UNITED STATES PATENT OFFICE

106,825

DESIGN FOR A DRESS ENSEMBLE

Elizabeth M. Ciccone, New York, N. Y.

Application September 15, 1937, Serial No. 71,625

Term of patent 3½ years

To all whom it may concern:

Be it known that I, Elizabeth M. Ciccone, a citizen of the United States of America, residing in city of New York, county of New York, and State of New York, have invented a new, original, and ornamental Design for a Dress Ensemble, of which the following is a specification, reference being had to the accompanying drawing, forming part thereof.

Fig. 1 is a front view of a dress ensemble showing my new design.

Fig. 2 is a front view of the dress portion of the ensemble.

Fig. 3 is a rear view thereof.

The rear view of the jacket is conventional.

I claim:

The ornamental design for a dress ensemble, substantially as shown and described.

ELIZABETH M. CICCONE.
